UNITED STATES PATENT OFFICE.

ALVA THOMAS SMITH, OF WINSTED, CONNECTICUT.

DESIGN FOR A GUARD FOR ELECTRIC HEATERS.

Application filed August 14, 1923. Serial No. 7,004. Term of patent 3½ years.

To all whom it may concern:

Be it known that I, ALVA THOMAS SMITH, a citizen of the United States, and a resident of Winsted, in the county of Litchfield and State of Connecticut, have invented a new, original, and ornamental Design for Guard for Electric Heaters, of which the following is a specification, reference being had to the accompanying drawing, forming part thereof.

Figure 1 is a front elevation of a guard, showing my new design.

Figure 2 is a side view of the guard shown in Figure 1.

1 claim:

The ornamental design for a guard for electric heaters, as shown.

ALVA THOMAS SMITH.
